UNITED STATES PATENT OFFICE.

ARTHUR J. BRADLEY, OF SAN FRANCISCO, CALIFORNIA.

VENTILATOR.

1,272,202.

Specification of Letters Patent. Patented July 9, 1918.

Application filed December 15, 1917. Serial No. 207,635.

To all whom it may concern:

Be it known that I, ARTHUR J. BRADLEY, a citizen of the United States, residing in the city and county of San Francisco and 5 State of California, have invented a new and useful Improvement in Ventilators, of which the following is a specification.

My invention relates to improvements in 10 ventilators for port holes and the like wherever in a plurality of intercalary U-shaped members coöperate to form a series of tortuous channels for the passage of air and to prevent the passage of light and retard the passage of water; and the objects of my invention are—

First, to provide an improved ventilator for windows, port holes and the like adapted to permit the passage of air and prevent the passage of light;

20 Second, to provide an improved ventilator for ship's port holes and the like adapted to permit a free passage of air and retard a passage of water to prevent the flooding of a compartment or stateroom;

25 Third, to provide an improved device of the character described adapted to ventilate a stateroom or the like without exposing said room to the danger of becoming flooded from heavy seas;

30 Fourth, to provide an improved device of the character described adapted to drain water from the channels to the outer side of the device; and

35 Fifth, to provide an improved ventilator adapted to permit the passage of air, prevent the passage of light and to retard the passage of water and having means for easily and readily securing said ventilator within an open port hole or the like.

40 I accomplish these several features by means of the device disclosed in the drawings forming a part of the present specification wherein like characters of reference are used to designate similar parts throughout the said specification and drawings, and in which—

Figure 1 is an elevation of the inner side of my improved ventilator;

Fig. 2 is a horizontal sectional view taken 50 on line 2—2 of Fig. 1;

Fig. 3 is an elevation of the outer side of the ventilator; and

Fig. 4 is a broken vertical sectional view taken on line 4—4 of Fig. 3.

55 Referring to the drawings the numeral 1 is used to designate a suitable circular frame

of the drum type, slightly conical to facilitate insertion into a port hole or the like, not shown.

The frame or drum 1 is provided with 60 equally spaced bifurcated lugs 2 by means of which the said drum may be readily attached and detached from within a port hole or the like.

Secured within the drum 1 are a plurality 65 of opposed and vertically disposed intercalary U-shaped members 3 a portion of whose flanges 4 are each offset an equal distance as at 6 to provide a series of tortuous passages 8 having enlarged chambers 7 adjacent said offset portions 6. The end of each offset portion 6 of each flange 4 is provided with a lateral flange 9 to reduce the entrance or exit of each enlarged chamber 7, the further purpose of which will herein- 70 after be more fully described.

Within each chamber 7 is mounted a vertically disposed V-shaped member 11 provided to further retard the passage of water through the said chambers 7. 80

The depth or width of the drum 1 is greater than the assembled U-shaped members 3 so that each edge of said drum 1 extends beyond the said U-shaped members 3 on the inner as well as the outer side of the 85 ventilator.

A draining shield or plate 12 is mounted across the lower inner side of the drum 1 so as to leave an air space between said plate 12 and the inner surfaces of the lower portions 90 of the members 3.

This plate 12 is provided to prevent the passage of water through the lower portions of the tortuous channels 8 into the room or compartment and to facilitate the drainage 95 of said lower portions of said channels to the outer side of the ventilator.

The drum 1 is provided with an annular flange 14 and a suitable gasket 16 to prevent the passage of water around the outside of 100 said drum when in position within the port hole.

The operation is as follows:

The tortuous passages 8 readily permit the passage of air for ventilation purposes 105 but prevent the passage of light rays whereby the various staterooms and compartments of a ship may be properly ventilated without displaying lights while passing through danger zones infested by submarines and 110 other hostile vessels.

During heavy weather a high sea will

frequently dash considerable water against the port holes of a ship requiring them to be closed and thereby prevent proper ventilation of the various compartments and state 5 rooms within the range of high waves and the like.

With the present invention installed within 10 a port hole the passage of air is readily permitted and the passage of light rays prevented by the tortuous passages 8. The said 15 passages 8 will also retard the progress or passage of considerable water as the sea or wave will generally subside before the pressure thereof has forced any water through 20 the entire lengths of the several tortuous passages 8.

Any water cast against the outer side of 25 the ventilator will first enter the outer ends of the tortuous passages or channels 8 and in entering the first series of enlarged chambers 7 will be retarded by the V-shaped members 11 which diverge toward the outer side of the ventilator. If the water proceeds beyond the first series of chambers 7 its passage will be further retarded by the lateral flanges 9 on the offset portions 6 of the flanges 4 of the U-shaped members 3.

Should the water then proceed farther 30 into the channels 8 to the second series of enlarged chambers 7 the V-shaped members 11 therein will still further retard the passage 35 of water.

After the subsidence of the wave or pressure there from any water within the channels 40 8 will naturally fall toward the bottom of lower ends of said channels. As the plate 12, being on the inside of the ventilator, will prevent the water from running into the room or compartment, said water 45 will be drained from the lower portion of said channels, such drainage being facilitated by the curvature of the lower half of the drum 1, to the outer side of the ventilator.

It is obvious from the foregoing that I 50 have provided an improved ventilator for port holes and the like adapted to permit the passage of air for ventilating purposes and prevent the passage of light rays which 55 would otherwise render a ship conspicuous, as well as retarding the passage of water through the port hole.

Having thus described my invention what I 60 claim as new and desire to secure by Letters Patent is—

1. A ventilator for port holes and the like comprising a plurality of intercalary U-shaped members arranged to provide a series of tortuous channels for the passage of air and to prevent the passage of light and retard the passage of water; and means for securing the intercalated members within a port hole or the like.

2. A ventilator for port holes and the like 65 comprising a plurality of opposed and verti-

cally disposed U-shaped members arranged to form a series of tortuous vertically disposed channels for the passage of air and to prevent the passage of light and to retard the passage of water; means for securing the members within a port hole or the like; and means for draining the channels to the outer side of said members.

3. A ventilator for port holes and the like 70 comprising a plurality of opposed and vertically disposed U-shaped members arranged to form a series of vertically disposed channels for the passage of air and to prevent the passage of light and to retard the passage of water; a circular drum inclosing the 75 U-shaped members; and a shield secured within the lower inner side of the drum and spaced apart from the U-shaped members to permit the passage of air and drain the channels to the outer side of the ventilator. 80

4. A ventilator for port holes and the like 85 comprising a plurality of opposed and vertically disposed U-shaped members arranged to form a series of vertically disposed channels for the passage of air and to prevent the passage of light and to retard the passage 90 of water; a circular drum inclosing the U-shaped members; and a shield secured within the lower inner side of the drum and spaced apart from the U-shaped members 95 to permit the passage of air and drain the channels to the outer side of the ventilator; and means for securing the drum within a port hole or the like.

5. A ventilator for port holes and the like 100 comprising a plurality of opposed and vertically disposed intercalary U-shaped members having flanges provided with inwardly offset portions, to form a series of vertically disposed tortuous channels, said offset portions 105 forming enlarged vertically disposed chambers within the channels, to permit the passage of air and prevent the passage of light and to retard the passage of water; vertically disposed V-shaped members 110 mounted within the enlarged chambers and diverging toward the outer side of the ventilator to obstruct the passage of water through the tortuous channels; means for draining the lower portions of the channels 115 to the outer side of the ventilator; and means for securing the ventilation within a port hole or the like.

6. A ventilator for port holes and the like 120 comprising a plurality of opposed and vertically disposed intercalary U-shaped members having flanges provided with inwardly offset portions, to form a series of vertically disposed tortuous channels, said offset portions 125 forming enlarged chambers within the tortuous channels, to permit the passage of air and prevent the passage of light and to retard the passage of water; vertically disposed V-shaped members arranged within the enlarged chambers and diverging to 130

ward the outer side of the ventilator to further obstruct the passage of water; outwardly extending flanges on the ends of the offset portions to further obstruct the 5 passage of water; means for draining the lower portions of the channels toward the outer side of the ventilator; a drum frame

surrounding the U-shaped members; and means for securing the frame within a port hole of the like.

In witness whereof I hereunto set my signature.

ARTHUR J. BRADLEY.
